JOSEPH P. McENERY, OF FLUSHING, NEW YORK

COMBINED PENCIL AND CLIP

Application filed August 14, 1930. Serial No. 475,178.

This invention relates to a combined pen- pencil, means for moving the pencil into a cil and a means for attaching a pencil or writing position, and means for holding the similar article to various objects, a specific pencil against movement with respect to the embodiment of the invention being a pencil clip members.

5 and clip designed for attaching the pencil to a golf score card or other objects.

My invention comprises a support or holder for a pencil or other article and means 10 associated with the support or holder whereby it may be secured to various objects. An important specific embodiment of the invention is a simple, convenient and handy pencil to be used with a golf score card and for like purposes, the pencil being readily attached to and detached from the card and 15 ordinarily carried with the card.

A further feature of my invention resides 20 in means for moving the pencil or other article to various desired positions with respect to the attaching means, for example, to a normal position in the clip and to a position for writing or other use, so that it may be in a position in which it is protected or out of the way or in a position in which 25 it may be easily used. Further features of the invention reside in the provision of means for holding the pencil or other article in desired positions with respect to the attaching means, and in the provision of means 30 for moving the pencil or other article from one such position to another.

My invention may be used in connection 35 with the pencil used in keeping golf or other scores. Pencils are usually carried loose with golf score cards and are continually being lost or misplaced, and it is believed by means of my invention that much of the inconvenience normally incident to keeping golf scores may be averted. It is to be understood, how- 40 ever, that my invention is not limited to use with pencils for golf or other score cards, but it may be used with other objects of similar shape and with program or book or the like with which its use would be desirable or 45 convenient.

A specific embodiment of my invention de- 50 scribed for the purpose of illustrating the invention, but to which the invention is not limited, comprises a pencil, preferably flat, clip members which normally embrace the

pencil, means for moving the pencil into a writing position, and means for holding the pencil against movement with respect to the clip members.

Other objects, novel features and ad- 55 vantages of my invention will be apparent from the following specifications and accompanying drawings, wherein

Fig. 1 is a general plan view of a card showing the pencil attached thereto; 60

Fig. 2 is a side view of Fig. 1 showing the clip in position;

Fig. 3 is a sectional view of Fig. 1 on the line "3—3";

Fig. 4 is a front view of the pencil and 65 clip detached;

Fig. 5 is an enlarged fragmentary detail view of Fig. 4, partly in section;

Fig. 6 is a cross-section of Fig. 5 on the line "6—6";

Fig. 7 is an enlarged fragmentary detail view of a modified form, partly in section;

Fig. 8 is a fragmentary detail view of the modified form shown in Fig. 7, showing the 75 arrangement of the clip members;

Fig. 9 is a sectional view of Fig. 7 on the line "9—9";

Fig. 10 is a front view of another modified form of the pencil and clip, as detached;

Fig. 11 is an enlarged fragmentary per- 80 spective view of the form shown in Fig. 10;

Fig. 12 is a side elevation of the form shown in Fig. 10, and showing pencil in writing position;

Fig. 13 is an enlarged fragmentary detail 85 view of a further modified form, with parts cut away to expose the construction;

Fig. 14 is a sectional view of Fig. 13 on the line "14—14";

Fig. 15 is a front view of another modi- 90 fied form; and

Fig. 16 is a detailed view of the construction of the retaining member shown in Fig. 15.

Throughout the description and claims be- 95 low, wherever the word "pencil" is used, it is to be understood that any other small straight implement which it would be useful or desirable to have mounted in the same manner, may be substituted for the pencil, and where "writ-

ing purposes" or "writing position" is used, it is to be understood that such other purposes and similar position of other use may be substituted as would conform to the use 5 of the substituted article.

- In Figs. 1-6, 20 indicates a card of the common golf score card type, comprising a strip of cardboard, folded in the middle to form two plies 21 and 22. A short pencil or other article 23, preferably flat, is held by base member 24, which is pivoted about a pintle 25. The pintle 25 is firmly held at its ends by the drums 26 and 27, to which are rigidly connected the clip members 28 and 29. The 10 clip members 28 and 29 are preferably composed of wires, slightly flexible, which embrace the pencil or other article 23, when in normal position, and are bent around the tip of said pencil or other article, the outer ends 15 of said clip members being slightly flared to permit ingress of the card plies 21 and 22. As seen in Figs. 1, 2 and 3, the pencil and clip are preferably carried on the card by inserting the pencil between the two plies of the card, 20 25 and 22, with the clip members 28 and 29 outside the card plies and gripping them closely about the pencil. When it is desired to use the pencil, the pencil and clip are drawn from the card, a retaining device released 25 and a spring mechanism then swings the pencil through a 180° arc into a writing position. It is possible, however, to use other methods of placing the pencil in writing position, such as the sliding arrangement shown 30 35 in Fig. 15, which do not involve a spring mechanism which swings the pencil through a 180° arc, and my invention is not to be limited to use of such spring mechanism.
- I have shown several preferred forms of 40 the spring mechanism whereby the pencil is snapped into writing position by swinging through a 180° arc on operation of the releasing device, all of which are practical adaptations of my idea, but it is to be understood 45 that other methods of swinging the pencil through a 180° arc into writing position may be devised with and without the use of a spring and without departing from the spirit of my invention. In Figs. 5 and 6, one 50 form of spring mechanism is shown in detail, wherein the spiral spring 30 is wound around the pintle 25, one end of which spring is secured to the pintle at the point 31, and the other end to the side of the base member 24 55 at the point 32. A projecting piece or ear 33 is pressed out of one side of the base member 24, which fits into a natural recess formed by the two clip members 28 and 29, and comprises the retaining mechanism, 60 which holds the pencil in position between the clip member 28 and 29, against the tension of the wound spring 30. A similar projecting piece or ear 34 is formed on the base member 24 at a corresponding point beyond the 65 pintle 25 and diametrically opposite the ear

33, which serves the same function of holding the pencil in position, when the pencil has swung through a 180° arc and the spring 30 has become unwound. To prevent the pencil from being swung except back and forth 70 through its original 180° arc, and thereby to prevent the spring 30 from being broken, a lug 35 is pressed out from the underside of the base member 24, which moves in the groove 35' cut out along half the circumference of the lower drum 27. The retaining mechanism, when the pencil is in closed position, is disengaged merely by pressure of the finger against the pencil, the spring 30 swinging the pencil around the pintle 25 through 75 a 180° arc into writing position, and by similar pressure the ear 34 is made to engage the recess between the clip members 28 and 29, thereby holding the pencil in writing position. 80

In Figs. 7, 8 and 9, a second modified arrangement of my invention is shown, wherein the pintle 25 as a separate piece is dispensed with, and projections 36 and 37 of the clip members are made to serve the same purpose. 85 The clip members 28a and 29a are made as shown in Fig. 8 and are soldered together at 28' and 29' adjacent the projections 36 and 37 provided to form the pivot whereon the pencil is swivelled. As in the previous form of my invention, the spring 30a is coiled around the projections of the clip members forming the pivot, one end of the spring being attached to the projection and the other to the base member 24a. Ears 33a and 34a perform the same function as the corresponding ears in the previous form of the invention, and operate in the same manner and 33a' and 34a' are duplications thereof. As an alternative, 90 a bar 39 may be attached between the opposite sides of the clip member 29a at a point near the pivot end, which serves as a fulcrum, whereby side pressure upon the clip members beyond the fulcrum will cause the ends of the clip members near the pivot to expand, and thereby release the ears 33a and 38, and permit the spring 30a to swing the pencil into writing position. The bar 39 may also be attached to the first form of my invention 95 shown in Figs. 1-6. 100

A third form of my invention is shown in Figs. 10, 11 and 12, wherein a different form of retaining mechanism is provided. The clip members 28b and 29b are rigidly connected to the drums 26b and 27b. The base member 24b holding the pencil is fixedly mounted on the pintle 25b around which is coiled the spring 30b, one end of the spring being attached to the pintle and the other to the side of the base member, as before. The pintle 25b is pivotally mounted in the drums 26b and 27b, the lower drum 27b (Fig. 10) being held closely adjacent the base member 24b by a head 40 of the pintle, while the upper drum 26b is held spaced apart from the base 110 115 120 125 130 135

member 24b by the natural tension of the clip members 28b and 29b, and the length of the pintle 25b being sufficient, is movable longitudinally on the pintle 25b. The upper drum 26b is provided with a groove 41 disposed centrally across its end at right angles to the clip members 28b and 29b, and adapted to receive the lug 42 formed by bending over the top end of the pintle 25b. The top portion of the drum 26b nearest the pivot end of the clip is cut down to a height sufficient for the lug 42 to swing over it as the drum 26b is depressed and the pencil swings into writing position, while the other top portion on the other side of the groove 41 is maintained at a height sufficiently above the first portion that the lug 42 cannot clear the latter top portion, and the lug is consequently held by it, when the upper drum 26b is depressed on the pintle 25b to the full extent of the allowable distance. By this means, the pencil, when released, is permitted to swing into writing position through an arc of 180° and no more. The normal tension of the clip members 28b and 29b should be made sufficient to hold the lug 42 in the groove 41 of the upper drum 26b, and thereby hold the pencil in closed position, and to release the pencil and allow it to swing into writing position, it is only necessary to depress the clip members 28b and 29b at the loose side, which in turn allows the spring 30b to swing the pencil into writing position.

A fourth modification of my invention is shown in Figs. 13 and 14, wherein a different form of spring mechanism for turning the pencil into writing position is provided, dispensing with the coiled spring, and in which extensions of the clip members displace the pintle. In this form, two resilient members 43 and 44 are pressed out from the sides of the base member 24c to form tongues which engage two bent over ends 45 and 46 of clip members 28c and 29c. The clip members 28c and 29c are made as before except that one end 36c and 37c of each clip member is projected to form a pivot, as in my second modified form, shown in Figs. 7, 8 and 9, and the end of each projection is bent over to form a lug 45 and 46, in a direction longitudinal of the clips and in addition the other end of each clip member is terminated at the base of the projection 36c and 37c and there soldered. In this form, the swinging of the pencil through a 180° arc from closed position into writing position is not automatic as in the forms in which a coiled spring is used, but the pencil is turned over manually against the resistance of resilient members 43 and 44 engaging the lugs 45 and 46, the resilient member 43 and 44 tending to hold the pencil either in closed position or in writing position and resisting intermediate movement.

A fifth form of my invention is shown in Figs. 15 and 16, wherein the method of placing

ing the pencil in writing position by swinging the pencil through a 180° arc is departed from entirely, and a sliding arrangement is employed, whereby the pencil is moved from closed position into writing position by merely sliding it longitudinally along the sides of the clip members 28d and 29d. The clip members 28d and 29d are formed practically as before, except that their tip ends are more sharply flared to permit passage of the pencil through them and their base ends are soldered together. The base member 24d, holding the pencil, can be formed of a single flat strip of metal cut out and bent as indicated in Fig. 16. The sides 47 and 48, the base 49, the top side 50 and bottom side 51 are bent to form a receptacle into which the base of the pencil may be inserted and closely contained, and the pencil with base member 24d placed in position inside the clip members, and the top and bottom flaps 52 and 53 are then bent over covering the clip members, and forming a groove whereby the base member may be slid at will along the length of the clip members.

While I have disclosed several preferred forms of construction, it will be understood that the invention is not to be limited to these details of structure, as it is apparent that various other modifications may be made in the structure of the device without in any way departing from the spirit of the invention as defined in the appended claims. 95

I claim:—

1. A device of the character described comprising a holder for a pencil or other article of similar shape, and a pair of clip members attached at their ends to said holder for movement relative to the holder, said clip members being adapted to clasp the plies of a folded article with a pencil interposed between the plies. 100 105

2. A device of the character described comprising a holder for a pencil or other implement of similar shape, and a pair of clip members connected at one end to said holder for unitary movement relative thereto, said clip members being adapted in one position to embrace the pencil or other implement carried by the holder and in another position to constitute an extension of said pencil or other implement. 110 115

3. A device of the character described comprising a pair of clip members connected at one end, and a holder for a pencil or other implement of similar shape pivotally supported by said clip members, said clip members being adapted in one position to embrace said pencil or other implement and in another position to constitute an extension thereof. 120 125

4. A device of the character described comprising a pair of clip members connected at one end, a holder for a pencil or other implement of similar shape pivotally support- 130

ed by said clip members, said clip members being adapted in one position to embrace said pencil or other implement and in another position to constitute an extension thereof, resilient means tending to swing the holder from the first position into the second position, and yieldable means for holding said holder in the first position.

5. A device of the character described comprising a pair of clip members connected together at one end, and a holder for a pencil or other implement of similar shape slidably connected to said clip members, said clip members being adapted in one position to embrace said pencil or other implement and in another position to constitute an extension thereof.

6. A device of the character described comprising a holder for a pencil or other article of similar shape, and a pair of clip arms attached adjacent their ends to said holder for swinging movement relative thereto, said clip arms being adapted to clasp the plies of a folded article with the pencil interposed between said plies.

7. A device of the character described comprising a pair of clip arms, and a holder for a pencil or other article of similar shape slidably supported by said clip arms, said clip arms being adapted to clasp the plies of a folded article with a member carried by said holder interposed between said plies.

In testimony whereof, I have signed my name to this specification.

35 JOSEPH P. McENERY.
